UNITED STATES PATENT OFFICE.

JOHN WILEY, OF SAN ANDREAS, CALIFORNIA.

IMPROVEMENT IN HAY-PRESSES.

Specification forming part of Letters Patent No. **158,344**, dated December 29, 1874; application filed November 18, 1874.

To all whom it may concern:

Be it known that I, JOHN WILEY, of San Andreas, Calaveras county, State of California, have invented an Improved Hay-Press; and I do hereby declare the following description and accompanying drawings are sufficient to enable any person skilled in the art or science to which it most nearly appertains to make and use my said invention or improvement without further invention or experiment.

My invention relates to an improved hay-press, which is very simple in construction, and which can be easily operated by one man; and it consists in the combination of devices more fully described in the following specification, in which reference is had to the accompanying drawing, in which—

Figure 1 is a perspective view of my press. Fig. 2 is a view of a part of the follower-guides. Figs. 3, 4 are sections of the press.

A is the upright body or press-box, having an open top, and inside of which the hay or other loose material is placed to be pressed. B is the platform or apron, which receives the hay when it is pitched into the press. Above the box or body A I construct a frame, which consists of the upright timbers C and the upper cross-timber D. The upright timbers C are secured opposite to each other to the middle of the sides of the box at each side of the apron; and each timber may consist of a single timber, having a vertical slot, e, passing upward through its middle, or of two parallel timbers placed far enough apart to provide the necessary slot. The follower F is secured to the lower end of a frame, consisting of the upright side timbers G and upper cross-beam H. The cross-beam H extends out upon each side of the upright timbers G far enough to enter the slots e in the upright guide-timbers D, in which slot they move in order to guide the movement of the follower. Upon the upper cross-timber D of the body-frame I mount two pulleys, h h', the pulley h being nearly over the middle of the timber, while the pulley h' is over one end. A rope or cord, I, is secured to the middle of the cross-beam H of the follower-frame, and passes up over the pulley h, thence over the pulley h', and down to the shaft j of a windlass, to which it is secured, so that by turning the crank K of

the windlass the rope or cord will be wound up, and the follower raised until its cross-beam is drawn to the upper end of the slot e. One end of a cord, l, is secured to each end of the cross-beam H of the follower-frame outside of the upright C, and passes down around a pulley, m, near the bottom of the press-box, and thence passes upward to spirally-grooved cone-pulleys n, which are formed on the opposite ends of the shaft O, to which their opposite ends are attached. A large hand-wheel, P, which is constructed similar to a pilot-wheel, is secured on one end of the shaft O, so that by turning this wheel the shaft, with its cone-pulleys, will be rotated, and the cords or ropes e wound upon them, so as to draw the follower down toward the bottom of the box A.

In order to give sufficient lightness and strength to the wheel P, I make the outside rim q of wire, by carrying two parallel wires around the wheel, and winding them around each arm successively. I then twist the two parallel wires together between each two arms, so as to tighten them, and thus brace and unite the arms together. P' is the door, at one side near the bottom of the press-box, through which the pressed bale is removed.

To remove the bale, I employ a lever, Q, on the side of the press-box opposite the door. One end of this lever is pivoted in the end of a projecting bar, R, at the corner of the box, while at its middle one end of a punch, S, is attached. This punch can be inserted through a hole in the side of the press-box, so that its end will bear against the rear side of the bale, when, by applying power to the end of the lever, the bale will be forced out through the door. A pawl-bar, T, is attached to one of the base timbers of the press just below the hand-wheel P by a screw or bolt, which passes through a slot between the middle and one end of the bar, and passes into one edge of the timber. The long end of this bar is of sufficient length to rest on the opposite timber, when the bar is placed horizontally and moved toward it; but when the bar is moved in an opposite direction the length of the slot in the long end will drop off of the opposite timber, and raise the short end, so that it will act as a pawl to hold the wheel in any desired

position by acting against the end of its arms as they successively pass it.

In baling hay with this machine, I raise the follower by means of the windlass until its cross-beam is drawn to the upper ends of the slot *e*. An enlarged opening, *V*, is made in the slot at this point, which will allow the square ends of the cross-beams *H* to turn in it. I then swing the follower away from over the upper open end of the box and lower on the windlass, until its edge rests on the side of the box, so as to provide an inclined side-board opposite the platform or filling side, which will prevent the hay from being pitched entirely over the press.

When the box is filled I tramp the hay down and replace the follower over the mouth of the press. Power is then applied to the hand-wheel, and the follower is drawn downward, compressing the hay into a bale, after which it is bound and removed by my lever-purchase, as above described.

This hay-press can be easily worked by one

man, can be made quite cheaply, and will press hay with great power and facility.

Having thus described my invention, what I claim, and desire to secure by Letters Patent, is—

1. The press-box *A*, with its slotted uprights *C* and cross-timber *D*, in combination with the follower *F*, with its side timbers *G* and cross-beam *H*, said cross-beam having projecting arms which move in the slot *e*, the whole operated by cord *I*, shaft *j*, cord *l*, pulley *m*, and the shaft *O*, with its cone-pulleys *n* and hand-wheel *P*, substantially as and for the purpose described.

2. The slotted pawl-bar *T*, arranged as described, in combination with the hand-wheel *P*, substantially as and for the purpose specified.

In witness whereof I have hereunto set my hand and seal.

JOHN WILEY. [L. S.]
